US00D799349S

(12) **United States Design Patent** (10) Patent No.: **US D799,349 S**
Mathier et al. (45) Date of Patent: **** Oct. 10, 2017**

(54) **LENGTH MEASURING INSTRUMENT**

(71) Applicant: **TESA SA**, Renens (CH)

(72) Inventors: **Anna Mathier**, Rolle (CH);
Alessandro Nardulli, Bevaix (CH)

(**) Term: **15 Years**

(21) Appl. No.: **35/501,237**

(22) Filed: **Jan. 18, 2016**

(80) **Hague Agreement Data**

Int. Filing Date: **Jan. 18, 2016**

Int. Reg. No.: **DM/089520**

Int. Reg. Date: **Jan. 18, 2016**

Int. Reg. Pub. Date: **Jul. 22, 2016**

(51) LOC (10) Cl. **10-04**

(52) U.S. Cl. **D10/70**

(58) **Field of Classification Search**

USPC **D10/57, 78, 70, 49, 103**

CPC **G01B 5/00**

See application file for complete search history.
